UNITED STATES PATENT OFFICE.

JOSEPH PAIL, JR., OF PRAGUE, ALBERTA, CANADA.

SHELL.

1,229,506.

Specification of Letters Patent. Patented June 12, 1917.

Application filed January 21, 1916. Serial No. 73,325.

To all whom it may concern:

Be it known that I, JOSEPH PAIL, Jr., a subject of the King of England, residing at Prague, Alberta, Canada, have invented 5 a new and useful Shell, of which the following is a specification.

This invention relates to explosive shells or projectiles and has for its object the provision of a novel and improved triple action 10 shell which can be used not only as shrapnel but also, as a grenade.

It is also within the scope of this invention to provide a very efficient shell, simple and inexpensive in construction.

15 With the foregoing and other objects in view which will be apparent from the illustrations and description, the present invention finds embodiment in the novel combination and arrangement of parts and members and in the details of construction herein shown, described and more particularly pointed out in the appended claims.

An illustration of my invention is found 20 in the accompanying drawings, wherein:—

25 Figure 1 is a longitudinal section of a shell constructed according to my invention; and

30 Figs. 2 and 3 are cross sections, taken respectively on lines 2—2 and 3—3 of Fig. 1.

35 Fig. 4 is an elevation of the bomb in the lower or base chamber.

The shell comprises a cylindrical wall 5 cast with a partition or diaphragm 6 which is dished or concave on both sides and 40 provided with a small central opening for the short connecting fuse-tube 7.

One end of the cylinder 5 is screw-connected with the head 8 which may have both time and percussion fuses whereby the 45 shell may be set off or fired at a certain time or distance from the projecting ordnance or shot as a grenade.

I have preferred to illustrate herein a time-fuse construction comprising a hammer 45 carrying a primer 10 which is forced by the set back to strike the point 11 of the anvil 12 and cause a flame to travel by the time-ring 13 and channel 14 to a highly explosive charge 15 held within the head 8 by a disk 16.

50 The impact or percussion-fuse comprises a primer 17 held within anvil 12 and adapted for detonation by the momentum of the pointed hammer 18, causing the igniting flame to pass through port 19 and passage 14 to ignite charge 15.

Before affixing the head 8 to cylinder 5 a charge-disk 20 of paper or other very thin and inflammable material filled with a high explosive, or charge and having oppositely 60 bulging convex sides 20^A, conforming to the curvature of the diaphragm and with flattened edges 20^B, is placed on the dished diaphragm 6 so that the projecting fuse-tube 7 perforates the charge-disk 20 to afford communication with a similar charge disk 21 on the other side of the diaphragm 6 in the base-chamber.

A castiron disk 22 is next placed on top of the charge-disk 20. This iron disk 22 has 70 a curved side arranged to fit over the side 20^A of the charge-disk 20 and the flattened edges 20^B against the diaphragm 6.

A thin tube 23 having a supporting shoulder 23^A, containing a quickly ignitable fuse, 75 is next inserted into the small central opening of disk 22 to perforate the charge disk 20 and rest shoulder 23^A on top thereof. After the balls or shot 24^A are filled in around same, the complete head 8 is screwed 80 on, the cone head 23^B fitting securely into the converging opening within the disk 16.

The filling of the base chamber may be described as follows:

After the insertion of charge-disk or 85 charge 21 through the rear end of cylinder which is closed by the back 25 having a screw connection therewith, the complete bomb member 26 is inserted to confine the charge 21 in a similar manner to the disk 90 22 in the upper chamber. The large balls or shot 24^B are then filled in around same.

The bomb member 26 comprises the dished head 26^A similar in construction to disk 22 and having a cylindrical body 26^B closed by 95 the screw connected back 26^C. An interior round-headed cylindrical charge 27 filled with an explosive 29 is securely held against the head by means of the screw 28 carrying a time fuse which acts to communicate the 100 ignition from charge 21 to charge 29. The charge 27 being filled through the rear end which is provided with a screw connected back 27^A. A quantity of small balls or shot 30 are filled in between the charge 27 and 105 interior of body 26^B.

Several small pyramids, 26^D, or the like may be cast on the exterior of the body 26^B, to confine the bomb to a relatively central position within the base chamber.

110 After the shell is shot from the projecting piece of ordnance, the time fuse will

ignite the explosive charge 20 in the head chamber through the medium of charge 15 and tube 23, which will finally explode and scatter the smaller shrapnel balls within 5 same.

Should the time fuse for any reason become inactive an ordinary percussion fuse may be provided as shown to explode the shell when striking.

10 It is obvious that the fuse-tube 7 could be omitted and the two explosive charges 20 and 21 placed directly in between the diaphragm 6 and the disk 22 and bomb head 26^A the two charges communicating through 15 the ordinary opening in the center of the diaphragm.

Likewise various other simple changes may be made in the construction of the various members without departing from the 20 spirit of my invention.

I claim as my invention:

1. A triple action shell comprising a head chamber, a base chamber, an explosive charge and shrapnel balls in each chamber 25 and a bomb in the base chamber, said bomb having an independent explosive charge in communication with the explosive charge of the base chamber, said charges and bomb arranged for successive explosion.

30 2. A triple action shell comprising a head chamber, a base chamber, an explosive charge and shrapnel balls in each chamber, and a bomb in said base chamber, said bomb having an independent explosive charge in 35 communication with the explosive charge of the base chamber, said charges and bomb charge arranged for successive explosion and said charges being adjacent and interconnected.

40 3. A triple action shell comprising a cylindrical body having a diaphragm within dividing the interior into a head chamber and a base chamber, an opening in said diaphragm, an explosive charge on each side 45 of said diaphragm, said charges communicating through said opening, shrapnel balls in said chambers, a bomb in said base chamber, said bomb having an independent explosive charge in communication with the 50 explosive charge of the base chamber, said charges and bomb arranged for successive explosion.

4. A triple action shell comprising a cylindrical body, a diaphragm within said 55 body dividing the interior thereof into head

and base chambers, an opening in said diaphragm, explosive charges on both sides of said diaphragm, said charges communicating through said opening, shrapnel balls in said chambers, a bomb in said base chamber 60 having an independent explosive charge directly communicating with said explosive charge in said base chamber, said charges and bomb arranged for successive explosion.

5. A triple action shell comprising a cylindrical body and a fuse-head therefor, a diaphragm within said body dividing the interior thereof into a head chamber and a base chamber, said diaphragm having concave sides and a concentric opening therein, 70 an explosive in each concave side, said charges communicating through said opening, a convex disk forming a cover for said charge in the head chamber, shrapnel balls between said cover and fuse-head, a quickly- 75 acting fuse connecting said fuse head with said charge in said head chamber, a bomb having a concave head adapted to house said charge in said base chamber, an explosive charge in said bomb communicating with 80 said charge in said base chamber, shrapnel balls on the exterior of said bomb in said base chamber, and shrapnel balls within said bomb, said charges in said chambers and charge in said bomb arranged for suc- 85 ccessive explosion.

6. A triple action shell comprising a cylindrical body and a fuse-head therefor, a diaphragm within said body dividing the interior thereof into a head chamber and a 90 base chamber, said diaphragm having concave sides and a concentric opening therein, an explosive in each concave side, said charges communicating through said opening, a convex disk forming a cover for said 95 charge in the head chamber, shrapnel balls between said cover and fuse-head, a quickly-acting fuse connecting said fuse head with said charge in said head chamber, a bomb adapted to house said charge in said base 100 chamber, an explosive charge in said bomb communicating with said charge in said base chamber, shrapnel balls on the exterior of said bomb in said base chamber, said charges in said chambers and charge in said 105 bomb arranged for successive explosion.

In witness whereof I have hereunto affixed my signature this 13th day of January A. D. 1916.

JOSEPH PAIL, JR.
